CONSTRUCTION OF CAST POSTS, AND PARTICULARLY THE CONSTRUCTION OF CONCRETE STRUTS BY MEANS OF METALLIC FRAMES

Roger Huet, Paris, France, assignor to Blaw Knox Company, Pittsburgh, Pa.

Filed Mar. 31, 1953, Ser. No. 345,917

Claims priority, application France Aug. 12, 1952
1 Claim. (Cl. 25—121)

The invention relates to the construction of cast posts, and particularly the construction of concrete struts by means of metallic frames.

The construction of concrete struts is one of the problems most often met with in public works and building construction. This problem is however often of difficult solution owing to the great variety presented by the section of these struts, while the metallic panels used for the frames have standardised dimensions.

Up to now, this problem has been solved in two different manners.

A first solution consists in using panels of various dimensions. It is then possible to connect together panels of different dimensions and obtain in this manner struts of varied dimensions. For example, by using in combination panels of 10, 15, 20, 25 and 50 centimetres, it is possible to construct struts the sides of which vary in length by steps of 5 centimetres. However, the use of such a large number of panels is objectionable in practice.

The second solution consists in shutting the struts by means of panels of standard dimensions so disposed that the free edge of a panel abuts against one of the adjacent panels and that the latter panel itself constitutes an abutment for another adjacent panel. In this case, the panels abutting against each other are connected at the corners by gussets placed on the edge of the panels between two superposed tiers of frames.

This arrangement is an improvement on the former one, but it nevertheless still has drawbacks. As a matter of fact, in order to avoid chinks in the framework, it is necessary to place, between the gussets and the edges of the panels, packings which form joints between the gussets. These packings must have varied sizes in order to allow for the varied panel sections and this leads to the provision of sets of packings of different dimensions. In short, the difficulty has but changed its nature and, instead of having to deal with sets of panels, one has to deal with standard dimension panels but with relatively numerous sets of packings.

The invention has for its object to obviate the drawbacks of the metallic frames hitherto in use, and to allow the use of metallic panels of standard size and assembling gussets which do not require sets of packings.

According to the invention, two successive slabs of panels are connected by stays constituted by flat sections, each flat section being provided with a gusset inside which slides one of the adjacent flat sections.

The flat sections and the panels may besides be provided with orifices serving to anchor them to each other.

The invention will now be described in greater details with reference to the accompanying drawings, which represent a preferred embodiment given by way of example.

FIG. 1 is a plan showing the manner of anchoring the panels in one of the methods formerly in use, necessitating the use of packings blocking the chinks between the gussets.

FIG. 2 is a part section of a frame according to the invention.

FIG. 3 is a plan of an assembling gusset.

FIG. 1 shows panels 1, 2, 3 and 4 abutting against each other by one of their free edges. A slab of frame is assembled with the next slab by means of angle gussets.

2

sets 5 connecting together the panels of a same slab. In order to avoid the chinks between the gussets, packings are disposed in the spaces existing between the gussets and the panel slabs.

5 In the assembly shown in FIG. 1 the packings are of two different dimensions, 6 and 7. It will be easily understood that there must be available packings of very varied dimensions in order to allow for the considerable variation taking place in the dimensions of the sections 10 of the struts.

FIGS. 2 and 3 relate to the frames according to the invention and one may ascertain from them that the packings 6 and 7 are entirely done away with and that only one kind of each member, that is to say one kind of 15 panel and one kind of assembling gusset is utilised. Of course, besides, some different dimensions may be provided in order to allow for very great variations in the sections of the struts, but on the one hand this is not indispensable, and on the other hand one may have only a 20 very small quantity of panels of different sizes.

The panels 8 are disposed in a similar manner to the panels represented in FIG. 1. On the horizontal edges of the panels are disposed metallic strips 9 (FIG. 3) provided with spaced perforations or openings 10 which permit on the one hand to fix these strips on the edges of the 25 panels and on the other hand to connect the panels to each other. Each strip 9 is provided with a gusset 11 which is in a different plane from the plane of the strip 9. Each gusset 11 is provided with a channel 12 the 30 width of which corresponds to the width of a strip 9 so that it is adapted to receive the latter.

In this manner, four strips 9 can be assembled, each one of these strips being engaged in the adjacent gusset 11. The arrangement represented in FIG. 2 is thus 35 obtained.

The gussets 11 are provided with a plurality of spaced 40 perforations or openings 13 adapted to receive pins which fix in position the strips 9 engaged in the channels 12 of the gussets.

According to the invention, the strips 9 are substituted 45 for the packings of varied dimensions 6 and 7.

The dimensions of the strut may be adjusted easily in 50 steps as small as desired owing to the number of perforations 10 and 13, provided in the strips 9 and the gussets 11, respectively.

45 The advantages of the arrangement described above are the following:

(a) The assembly of panels is made with a single kind 55 of packing of one dimension only and not with packings of multiple dimensions, as in the former arrangement.

(b) The dimensions of the strut may be adjusted with 60 a small approximation, this being dependent on the ratio of the spacing of the perforations in the panels and in the flat sections, respectively.

(c) The angular rigidity of the frames is ensured in a 65 perfect manner by the gussets.

It is well understood that the invention is not limited 70 to the embodiment described and represented in the drawings, which embodiment may be modified in details without departing from the scope of the invention, as defined by the claim.

What I claim is:

A metallic frame for casting concrete struts comprising 75 four like panels of standard dimensions arranged to enclose a rectangular quadrilateral the dimensions of which are adjustable, the said panels being disposed at right angles to each other with the end edge of one abutting against a face of the next inwardly of the adjacent end thereof, a metallic strip disposed on the horizontal edge of each panel externally of said opening and extending 80 between the two panels at right angles to the panel on which said strip lies, means connecting each strip to its 85

panel externally of the panel walls, a gusset fixed at one end of each metallic strip externally of the panels and having an open-ended channel disposed at a right angle to the longitudinal axis of the strip, each such channel being dimensioned to receive and engage the ungusseted end of the next contiguous metallic strip, each of the metallic strips and gussets being provided with a plurality of spaced perforations, and pin means for locking the strips and gussets in adjusted relationship through such perforations.
